UNITED STATES PATENT OFFICE.

WILLIAM HAWKER, OF EDMONTON, ALBERTA, CANADA.

SMOKESTACK.

1,382,508.

Specification of Letters Patent. Patented June 21, 1921.

Application filed December 3, 1920. Serial No. 428,141.

To all whom it may concern:

Be it known that I, WILLIAM HAWKER, a subject of the King of England, residing at Edmonton, in the Province of Alberta and 5 Dominion of Canada, have invented certain new and useful Improvements in Smokestacks, of which the following is a specification.

This invention relates to smoke jacks or 10 stacks for conveying the smoke from a locomotive when placed in position in a round house or shed to the outer atmosphere, and is designed as an improvement of the jack shown in Patent Number 1,322,565 issued 15 November 25, 1919.

The object of the invention is to provide simple and efficient means for moving the stack laterally and longitudinally relatively to the locomotive track and also vertically.

20 Another object is to provide a stack of this character composed of telescoping sections equipped with friction means to hold the telescoping section in any desired position, without jamming.

25 Another object is to provide a stack carrying truck equipped with a cover plate movable with the truck to protect the apparatus against rain, snow and the like.

With these and other objects in view, the 30 invention consists in certain novel features of construction as hereinafter shown and described, and then specifically pointed out in the claims, and in the drawings illustrative of the preferred embodiment of the invention.

35 In the accompanying drawing:

Figure 1 represents a side elevation of the apparatus constituting this invention shown applied to the roof of a locomotive shed, the 40 parts being broken away and in section.

Fig. 2 is a top plan view of the apparatus with the smoke stack in horizontal section.

Fig. 3 is an end elevation with parts broken out and parts in section.

45 Fig. 4 is a detail edge view of the friction means for holding the movable section of the smoke stack in adjusted position, parts being in section, and,

Fig. 5 is a side elevation thereof.

50 The apparatus constituting this invention is shown mounted in a locomotive shed or round house, the roof of which is indicated at 5 which is slotted at 6 for the passage therethrough of the stack shown as a whole 55 at 10 and which is designed to be positioned over the smoke stack of a locomotive and

conduct the smoke issuing therefrom to the outer atmosphere. This stack 10 is composed of telescoping sections 14 and 14^a, the upper section 14 being fixed and the lower 60 section 14^a movable vertically by means hereinafter to be described.

Truck supporting tracks 7 are carried by hangers 8 depending into the shed from the roof 5, said tracks being arranged above and 65 parallel with the locomotive track rails and below the slot in the roof, the latter being of a length substantially the same as the track 7, to provide for the movement of the truck to be described the full length of said 70 track.

A stack carrying truck 9 is equipped with double flanged wheels 10^a mounted to travel on the track rails 7, the double flanges of the wheels preventing spreading of the rails 75 or lateral displacement of the truck.

The truck 9 may be of any desired construction and carries in addition to the stack 10 a cover plate 15 to prevent the entrance of rain and snow through the slot in the roof. 80

A plate 17 is mounted to move transversely of plate 15 in guides 18 carried by plate 15 and said plate 17 surrounds the stack 10 and is secured thereto to provide for the lateral movement of the stack relatively to the locomotive track. 85

The truck 9 carries at its opposite ends depending arms 19 with the lower terminals of which are connected the ends of a cable 20. This cable 20 passes around pulleys 21 90 mounted on the hangers 8 and is designed for moving the truck longitudinally, a cable or chain 23 being provided for this purpose and passed over a grooved pulley 32 fixed to the shaft of one of the pulleys 21 and which 95 is of a length to permit it to hang within convenient reach of the operator so that when the wheel 22 is rotated in one direction or the other the desired longitudinal movement of the track 9 will be accomplished. 100

A suitably supported platform or truck 25 through which the stationary stack portion or section 14 projects is mounted to travel on transverse track rails 12 of the frame 105 structure of the main truck 9 to provide for the lateral movement of the stack relatively to the locomotive track rails.

An angular depending bracket arm or plate 27 is hingedly mounted at 27^a on a 110 pintle 27^b carried by the platform 25 and this plate pivotally supports at its lower end

a rock shaft 28 carrying spaced parallel crank arms 29 connected by relatively short links 30 with diametrically opposed trunnions 31 secured to the vertically movable 5 stack section 14^a.

A link 29^a is connected with each of the arms 29 by a friction clutch 50 shown in detail in Figs. 4 and 5 and which will presently be more fully described. Each link 10 29^a is pivoted to a fixed arm 51 bolted to the frame of the truck 25 as is shown clearly in Fig. 1.

The friction clutch 50 which connects arm 29 with link 29^a is composed of two cast iron 15 or steel disks 52 and 53 between which is disposed a wooden fiber disk 54 all of which are connected by a bolt 55 passing centrally therethrough and through arm 29 and link 29^a as is shown clearly in Fig. 4. A coil 20 spring 56 is mounted on the bolt 55 between its head and the link 29^a, the other end of the bolt outside arm 29 being equipped with jam nuts so that the disks are held in frictional engagement for a purpose presently 25 to be described, the tension of the spring 56 being adjustable to vary the engagement of the disks.

Each of the metal disks 52 and 53 is provided on its outer face with spaced laterally 30 projecting ribs 57 between which the arm 29 and the link 29^a are designed to be disposed.

The bracket or plate 27 being hinged at its top permits it to swing back and forth 35 so that all possibility of jamming of section 14^a of the stack is prevented, the movement of said stack section being perpendicular owing to this peculiar connection.

The shaft 28 has secured to its opposite 40 ends, arms 32 and 32' which carry at their terminals counterbalancing weights 33 and 33' which assist the arms 29 in the operation of actuating the vertically movable smoke stack section 14^a. A lever 34 is fixed midway 45 its ends to one end of shaft 28 and is equipped with cables as 35 positioned convenient to the operator.

From the above description it will be obvious that the friction clutch provided between links 29^a and arms 29 will operate to hold the adjustable section 14^a of the smoke 50 stack at any desired adjusted position and will be easily releasable by a pull exerted on a cable 35 secured to each end of the lever 34.

55 The lower end of the vertically movable stack section 14^a is flared as shown at 41 for convenience in positioning it over a locomotive stack and a section 42 of said lower end is cut out and hinged to adapt it to be tilted 60 out of normal position by the lateral withdrawal of the locomotive smoke stack from the stack 10 without injuring either.

Parallel laterally extending arms 36 are pivotally secured at one end to brackets 37 65 on the frame of truck 25. The outer ends of

these arms 36 are pivoted to the lower ends of depending crank arms 38 carried by a rock shaft 39, journaled in bearings 40 of a U-shaped bracket 43 fixed to the frame of truck 9. A lever 44 is fixed midway its ends 70 to shaft 39 the ends of which are conveniently accessible and oscillating the shaft 39 to laterally adjust truck 25 and the smoke stack 10 carried thereby.

The rods 45 connect the side members of 75 truck 9, as shown in Fig. 2, to strengthen the structure.

The preferred embodiment of the invention is disclosed in the drawings and set forth in the specification, but it will be understood that any modifications within the scope of the claims may be made in the construction without departing from the principle of the invention or sacrificing any of its advantages. 80

What I claim is:

1. The combination with a supplementary smoke stack including fixed and movable sections; of friction controlled lever and link means for moving said movable section 90 vertically without jamming.

2. The combination with a supplementary smoke stack including fixed and movable sections; of means for moving said movable section vertically without jamming, and friction means to hold said section operating means in adjusted position. 95

3. The combination with a supplementary smoke stack including fixed and movable sections; of means for moving said movable section vertically, and friction means to hold said section operating means in adjusted position. 100

4. A supplementary smoke stack adapted to be engaged with the smoke stack of a locomotive including a telescoping section, and friction controlled lever and link means for moving said section perpendicularly without jamming. 105

5. A supplementary smoke stack adapted to be engaged with the smoke stack of a locomotive including a telescoping section and means for moving said section perpendicularly without jamming, said means including fixed and pivoted arms with friction 115 clutches between said arms to hold the section in adjusted position.

6. A supplementary smoke stack for application to locomotives including a main truck, means movably supporting said truck, a supplementary carrier supported upon the truck and movable relatively thereto, a rock shaft carried by the supplementary carrier, a sectional smoke stack including an upper section secured to the supplementary carrier, 125 and a vertically movable lower section, means connecting the rock shaft with the lower stack section to permit vertical adjustment of the latter with relation to the upper section, and friction means connected 130

to maintain the vertically adjustable stack section in elevated or depressed position.

7. The combination with a smoke stack comprising fixed and movable sections; of a supporting structure therefor, arms depending from said structure, a rock shaft, arms pivoted at one end on said shaft, links pivotally connecting the other end of said arms to the movable section of the smoke stack, and a friction clutch connection between said first and last mentioned arms whereby said stack is held in adjusted position.

8. The combination with a smoke stack comprising fixed and movable sections; of a supporting structure therefor, arms depending from said structure, a rock shaft mounted to oscillate, arms pivoted at one end on said shaft, links pivotally connecting the other end of said arms to the movable section of the smoke stack, and a friction clutch connection between said first and last mentioned arms whereby said stack is held in adjusted position.

9. The combination with a smoke stack comprising fixed and movable sections; of a supporting structure therefor including trucks mounted to move in planes at right angles to each other, arms depending from the upper truck, a depending plate hingedly connected with said upper truck, a rock shaft journaled in said plate, arms pivoted at one end on said shaft, links pivotally connecting the other end of said arms to the movable section of the smoke stack, and a friction clutch connection between said first and last mentioned arms whereby said stack is held in adjusted position.

10. A supplementary smoke stack for application to locomotives including a supporting track, a carrier truck movable longitudinally of the track, a supplementary car-

rier movably supported upon the carrier truck, a sectional supplementary smoke stack, one of the sections being supported upon the supplementary carrier and the other section being vertically adjustable and telescopically engaged with the first mentioned sections, and friction controlled lever and link means to prevent jamming of the adjustable section.

11. A supplementary smoke stack for application to locomotives including a movable stack section, a movable support therefor, a rock shaft, arms connecting said shaft with the movable stack section, and friction means to hold the movable stack section in adjusted position.

12. A supplementary smoke stack for application to locomotives including a main truck, means movably supporting said truck, a supplementary carrier supported upon the truck and movable relatively thereto, a rock shaft carried by the supplementary carrier, and mounted to swing thereon, a sectional smoke stack including an upper section secured to the supplementary carrier and a vertically movable lower section, means connecting the rock shaft with the lower stack section to permit vertical adjustment of the latter with relation to the upper section, and friction means operable to maintain the vertically adjustable stack section in elevated or depressed positions.

13. In an apparatus of the class described, a supporting structure, a track carrying a truck mounted to travel thereon and provided with a cover plate movable with the truck to protect the apparatus against the weather.

In testimony whereof, I affix my signature hereto.

WILLIAM HAWKER.
